US0D1060028S

(12) **United States Design Patent** (10) **Patent No.:** **US D1,060,028 S**
(45) **Date of Patent:** **** Feb. 4, 2025**

(54) **WELDING CONSUMABLE CONTAINER**

(71) Applicant: **ESAB AB**, Gothenburg (SE)

(72) Inventors: **Claes Gimström**, Gothenburg (SE); **Roberto Carlos Guerrero Kees**, Frisco, TX (US); **Gerard F. Klaes**, Moab, UT (US); **Rodolfo F. Rep**, Hanover, PA (US); **Mikael Mimer**, Gothenburg (SE); **Michael Guion**, Mechanicsburg, PA (US)

(73) Assignee: **ESAB AB**, Gothenburg (SE)

(**) Term: **15 Years**

(21) Appl. No.: **29/909,512**

(22) Filed: **Aug. 7, 2023**

CLAIM

The ornamental design for a welding consumable container, as shown and described.

DESCRIPTION

FIG. 1 is an isometric perspective front view of a welding consumable container according to the present invention; FIG. 2 is an isometric perspective rear view of the welding consumable container of FIG. 1; FIG. 3 is a front view of the welding consumable container of FIG. 1; FIG. 4 is a rear view of the welding consumable container of FIG. 1; FIG. 5 is a right side view of the welding consumable container of FIG. 1; FIG. 6 is a left side view of the welding consumable container of FIG. 1; FIG. 7 is a top view of the welding consumable container of FIG. 1; and, FIG. 8 is a bottom view of the welding consumable container of FIG. 1.

1 Claim, 7 Drawing Sheets
